United States Patent Office

Des. 181,446
Patented Nov. 12, 1957

181,446

EMBOSSED AND PIERCED METAL SHEET MATERIAL

Richard S. Smith, Buffalo, N. Y., assignor to Rigidized
Metals Corporation, Buffalo, N. Y.

Application September 9, 1954, Serial No. 32,229

Term of patent 14 years

(Cl. D54—2)

Fig. 1.

Fig. 2.

Fig. 3.

Fig. 1 is an elevational view looking directly at the face of an embossed and pierced metal sheet material showing my new design;

Fig. 2 is a cross sectional view on the line 2—2 of Fig. 1; and

Fig. 3 is an elevational view looking at the opposite face of the sheet of Fig. 1.

I claim:

The ornamental design for an embossed and pierced metal sheet material, as shown.
